(57) **CLAIM**

The ornamental design for a hanger, as shown and described.

DESCRIPTION

FIG. 1 is a front perspective view of a hanger according to a first embodiment of my new design;

FIG. 2 is a rear perspective view thereof;

FIG. 3 is a front plan view thereof;

FIG. 4 is a back plan view thereof;

FIG. 5 is a left side view thereof;

FIG. 6 is the right side view thereof;

FIG. 7 is a top plan view thereof;

FIG. 8 is a bottom plan view thereof;

FIG. 9 is the right side view showing the hook rotated perpendicular to the hanger and showing the hanger in an illuminated state; and

FIG. 10 is the right side view showing the hook rotated perpendicular to the hanger and showing the hanger in a non-illuminated state.

FIG. 11 is a front perspective view of a hanger according to a second embodiment of my new design;

FIG. 12 is a rear perspective view thereof;

FIG. 13 is a front plan view thereof;

FIG. 14 is a back plan view thereof;

FIG. 15 is a left side view thereof;

FIG. 16 is the right side view thereof;

FIG. 17 is a top plan view thereof;

FIG. 18 is a bottom plan view thereof;

FIG. 19 is the right side view showing the hook rotated perpendicular to the hanger and showing the hanger in an illuminated state; and,

FIG. 20 is the right side view showing the hook rotated perpendicular to the hanger and showing the hanger in a non-illuminated state.

The oblique line shading on the top portion of the hanger represents a translucent material. The lines emanating from

(Continued)

the top portion of the hanger in FIGS. 9 and 19 depict illuminating light. The greyscale surface shading in FIGS. 11-19 represents a contrast in color from the top portion of the hanger, but does not represent a specific color. The broken lines (including the divots in the shoulder members and the hook) depict portions of the hanger that form no part of the claimed design.
